AIRCRAFT WINDSHIELD OR THE LIKE

Romey A. Gaiser and James H. Boicey, Toledo,
Ohio, assignors to Libbey-Owens-Ford Glass
Company, Toledo, Ohio

Application March 17, 1950, Serial No. 8,601

Term of patent 3½ years

(Cl. D71—1)

To all whom it may concern:

Be it known that we, Romey A. Gaiser and James H. Boicey, citizens of the United States, residing at Toledo, in the county of Lucas and State of Ohio, have invented a new, original, and ornamental Design for Aircraft Windshields or the like, of which the following is a specification, reference being had to the accompanying drawing, forming part thereof.

Fig. 1 is a perspective view of one side of an aircraft windshield, showing our new design; and

Fig. 2 is a perspective view of the opposite side of the same.

The drawing has been shaded to represent contrasting appearance.

We claim:

The ornamental design for an aircraft windshield or the like, substantially as shown and described.

ROMEY A. GAISER.
JAMES H. BOICEY.
